FRANK WILCOMB, OF NORRISTOWN, PENNSYLVANIA, ASSIGNOR TO WILDMAN MFG. CO.,
OF NORRISTOWN, PENNSYLVANIA, A CORPORATION OF PENNSYLVANIA.

TAKE-UP MECHANISM FOR KNITTING-MACHINES.

1,280,608.

Specification of Letters Patent.

Patented Oct. 1, 1918.

Application filed September 9, 1916. Serial No. 119,268.

To all whom it may concern:

Be it known that I, FRANK WILCOMB, a citizen of the United States, and resident of Norristown, Pennsylvania, have invented 5 certain new and useful Improvements in Take-Up Mechanism for Knitting Machines, of which the following is a specification.

One object of the invention is to provide a fabric takeup mechanism having a high 10 degree of sensitiveness adapting it for work with light fabrics, such for instance, as knitted tape. Knitted fabric which is to be used as tape for binding garments is made from fine yarn and the fabric being narrow 15 a takeup to work with such fabric must be of such a construction as will quickly respond to any slight extra tension on the fabric above that predetermined upon and will rapidly absorb or take up any slackness 20 which may occur in the fabric.

Takeup mechanisms which are intended for use with the usual wide fabric knit with the coarser yarns are not suitable for the character of goods with which the present 25 takeup mechanism is intended to work, not being delicate enough in either operation or adjustment.

To meet the requirements necessary in working with a light narrow fabric the present 30 invention has been devised and its subordinate objects and its novel characteristics will appear from the following description and the appended claims, taken in connection with the accompanying drawings, in 35 which,

Figure 1 is a side elevation of a knitting machine embodying my improved takeup mechanism.

Fig. 2 is a side view of the takeup mechanism detached from the machine.

Fig. 3 is a plan view of the takeup mechanism.

The takeup mechanism is driven from and directly associated with the main drive 45 shaft of the knitting machine, which drive shaft is indicated at 1 mounted in suitable bearings in the frame. This main drive shaft has a pulley 2 thereon, which through an upwardly extending belt 3 drives a pulley 4 on the shaft 5 suitably journaled in 50 the base of the knitting head. The fabric

indicated at X passes down from the knitting head between fabric rolls 6 and 7 located near the lower part of the main supporting frame 8 of the machine, which main frame is in turn supported by the legs 9. Of these fabric rolls the one marked 6 is positively driven, this roll being mounted in arms 10 of a pivoted support 11, the pivot of which is at 12 on the supplemental frame 13. The arms 10 provide a forked construction in which the fabric roll 6 is journaled. The other fabric roll 7 is journaled in a supplemental forked member comprising arms 14 and the main piece or cross bar 15, the main portion being pivotally mounted at 16 in the arms 10 of the main forked bracket or support 11. The main portion 15 of the supplemental bracket 14 has a shoulder at 17, which is engaged by a plunger 18 back 20 of which is a spring 19 upon which a plunger 20 presses, this plunger being adjustable by a screw 21. These plungers with the intermediate spring 19 are located in an opening or bore of the pivoted support or bracket 25 11 and by adjusting the screw 21 the tension of the spring 19 will be varied and therefore the tension exerted upon the roll 7 may be varied to suit different conditions.

As above stated the fabric passes down 30 between the two fabric rolls 6, 7. Its course taking it between the arms 14 of the supplemental bracket or fork. The fabric roll 6 is positively rotated and in order to provide a simple, effective and sensitive drive for this 35 roll I employ a friction driven wheel 22 of a diameter greatly in excess of that of the fabric roll 6. This friction wheel is mounted upon the extension of the shaft 6', that carries the fabric roll 6, the large friction 40 wheel being thus located as shown in Fig. 3 alongside of the pivoted bracket or support 11, which carries the fabric rolls. This large diameter friction driven wheel rests by 45 gravity upon a friction drive wheel or disk 23 mounted directly upon the main drive shaft 1 of the knitting machine. Preferably the large diameter driven wheel 22 is of metal having its periphery leather covered 50 while the drive wheel 23 is made up of a series of disks of leather or other suitable 55 material arranged side by side. The drive 60

wheel 23 is of considerably smaller diameter than the large driven wheel 22, the purpose of the relative diameters of the drive wheel 23, driven wheel 22 and the small fabric roll 6 being to secure a proper degree of leverage in transmitting the power to the takeup roll.

It will be observed that the fabric being gripped between the two fabric rolls 6 and 7, 10 if the tension on the fabric increases, the fabric rolls will have a tendency to climb on the fabric and thus reduce the frictional drive pressure between wheels 22, 23 and the rotation of the wheel 22 will be reduced or 15 it will cease momentarily until the production of fabric at the needles has relieved the tension and then the friction wheel 22 will resume its normal frictional contact with the drive wheel 23 and the takeup action 20 will proceed at the normal rate. The wheel 22 is therefore rotated intermittently according to the demands of the takeup strain.

While as above stated, the fabric rolls tend to climb on the fabric actual separation 25 of the driven friction wheel 22 from the drive wheel 23 does not necessarily take place, as the reduction in friction pressure will cause the slowing down or cessation in the revolution of the large diameter friction wheel 22 and consequently the reduction or cessation of the takeup action. The fabric roll 7 being under spring tension will 30 yield for the passage of extra thicknesses of the fabric accommodating itself automatically to variations of this character.

What I claim is:—

1. In combination in takeup mechanism for knitting machines, a constantly rotating driving member on a horizontal axis and 40 mounted on the fixed frame of the machine, a driven member also on a horizontal axis and mounted on the fixed frame, said members engaging each other at their peripheries, a takeup roll connected with and actuated from the driven member, the driving engagement between the said members varying in accordance with variations in the tension of the fabric, substantially as described.

50 2. In combination in takeup mechanism for knitting machines, a drive member rotatable about a fixed horizontal axis, a driven member also rotatable about a horizontal shaft upon which the said driven member is mounted, a movable support for 55 said driven member to allow the same by gravity to rest with its periphery in contact with the periphery of the driving member, said support being mounted on the fixed frame, a takeup roll actuated by the driven member, and arranged coaxially therewith and upon the same shaft, said roll engaging the fabric on one side and a roll engaging the fabric on the other side and carried by 60 said movable support, said rolls gripping

the fabric between them and tending to climb on the fabric and relieve the contact pressure between the driving and driven members, when the tension of the fabric increases, substantially as described. 70

3. In combination in a takeup mechanism for knitting machines, a main drive shaft for the knitting machine, a pulley thereon, a belt extending up from said pulley, a driven pulley engaged by said belt, a wheel 75 on the main drive shaft, a driven wheel resting thereon by gravity, a fabric roll on the shaft of the driven wheel and means for holding the fabric against said roll to be taken up thereby, the rotation of said roll varying in accordance with the variations in the frictional pressure between the driven friction wheel and the drive wheel consequent upon variations in the tension of the fabric, substantially as described. 80

4. In combination in takeup mechanism for knitting machines, a pivoted forked support, a fabric roll mounted between the arms of said fork, a friction driven wheel outside the said fork and mounted on the 90 shaft of the fabric roll, a supplemental fork pivoted in the main fork, a second fabric roll mounted in said supplemental fork and a drive wheel for the said wheel first mentioned and upon which drive wheel 95 said wheel rests by gravity, substantially as described.

5. In combination a drive wheel, a driven wheel, a forked bracket pivotally supported and carrying the shaft of the driven wheel, 100 a fabric roller mounted between the arms of the forked bracket, a supplemental forked bracket pivoted to the main bracket, a fabric roll mounted in the supplemental bracket and having a shoulder above its pivot, a 105 spring housed in the main bracket and exerting pressure against the shoulder of the supplemental bracket and means for adjusting the spring. 100

6. In combination in a takeup for knitting machines, a drive wheel arranged on a horizontal axis, a larger diameter driven wheel resting by gravity on the periphery of the drive wheel, a fixed frame, a movable support for said large diameter driven wheel 110 movably held by said fixed frame and a takeup roll of small diameter mounted coaxially with and on the horizontal shaft of the large diameter driven wheel, 115 substantially as described. 120

7. In combination in a takeup mechanism for knitting machines, a drive wheel on a horizontal shaft, a driven wheel on the horizontal shaft resting with its periphery and by gravity upon the periphery of the drive 125 wheel, a fabric roll coaxially arranged, connected with and actuated by the driven wheel, a second fabric roll gripping the fabric between itself and the first fabric roll and rotated by the said first fabric roll 130

through the fabric and a yielding mounting for the second fabric roll, substantially as described.

8. In a gravity takeup for knitting machines, a pair of fabric grip rolls, one of said rolls being pivotally mounted to open and close the space between the rolls, the pivoted grip roll being rotated by the frictional contact of the fabric between the 10 rolls, a friction driven wheel of large diameter connected with the driven fabric roll and a friction drive wheel of small diameter with means for constantly rotating the same, said drive wheel having peripheral contact with the wheel of large diameter, 15 the degree of pressure between the friction wheels being governed by the fabric tension and gravity, substantially as described.

In testimony whereof I affix my signature.

FRANK WILCOMB.
